UNITED STATES PATENT OFFICE.

RAFFAELE PINNAVAJA, OF BUFFALO, NEW YORK.

ATTACHMENT FOR ADJUSTING THE PITCH OF WIND MUSICAL INSTRUMENTS.

1,415,051.

Specification of Letters Patent.

Patented May 9, 1922.

Application filed February 28, 1921. Serial No. 448,332.

To all whom it may concern:

Be it known that I, RAFFAELE PINNAVAJA, a subject of the King of Italy, residing at Buffalo, in the county of Erie and State 5 of New York, have invented new and useful Improvements in Attachments for Adjusting the Pitch of Wind Musical Instruments, of which the following is a specification.

10 This invention relates to a pitch adjusting attachment adapted for wind musical instruments such as cornets, trombones, bassoons, saxophones, French horns, &c.

15 Its object is the provision of an attachment of this character which is self-contained and which is capable of being adjusted while in position on the instrument to which it is applied.

20 A further object of the invention is to provide a pitch adjuster which is simple in construction and which is easily adjustable, to effect a change of pitch in a minimum period of time.

25 In the accompanying drawings:

Figure 1 is a side elevation of a cornet equipped with my improvement. Figure 2 is a sectional elevation of the attachment, on an enlarged scale. Figure 3 is a vertical section on line 3—3, Fig. 2. Figures 4 and 5 are horizontal sections on the correspondingly numbered lines in Fig. 3. Figure 6 is a perspective view of a reed mouthpiece shown as applied to my improved pitch adjusting attachment.

35 Similar characters of reference indicate corresponding parts throughout the several views.

By way of example, the improvement is shown as applied to a cornet 10 of ordinary 40 construction, although it is to be understood that the same is applicable to various other wind instruments; for instance, trombones, bassoons, French horns, saxophones, &c.

45 The pitch adjusting attachment 11 is removably attached at its lower end to the stem 12 of the instrument while its upper end carries the usual mouthpiece 13. The attachment preferably comprises inner and outer telescopic members 14 and 15, respectively, both members being of tubular form and of substantially the same length. The inner member is movable lengthwise relatively to the outer member and carries 50 the mouthpiece of the instrument, while the outer member is stationary and is held fric-

tionally, or otherwise, in the stem of the instrument. By raising and lowering the inner member relatively to the outer member the pitch of the instrument is varied accordingly. The means for effecting this relative adjustment of the telescopic members are preferably constructed as follows:

The inner member 14 is provided throughout its length with an external screw thread 65 16, the external diameter of said inner member being somewhat less than the internal diameter of the outer member 15, so as to permit the inner member to move freely within said outer member. Rotatably 70 mounted at the upper end of the latter and co-operating with the threaded inner member to raise and lower the same relatively thereto is a sleeve or turning head 17 of hollow cylindrical form provided in 75 its upper portion with a nut 18 secured thereto by a pressed fit or any other appropriate manner. The lower end of this turning head is provided with an annular internal flange 19 which engages or interlocks 80 with a corresponding external flange 20 at the upper end of the outer telescopic member 15 while the nut 18 is arranged above the flange 20. By this construction, said turning head is held against longitudinal 85 displacement by reason of its flange 19 engaging the underside of the flange 20 and its nut 18 engaging the upper side of said last-named flange. In order to permit the turning head to rotate freely on said outer 90 telescopic member, a slight clearance is provided between the engaging parts.

To prevent rotation of the inner telescopic member 14 when the turning head 17 is rotated and yet permit its longitudinal movement relatively to its companion outer member, the latter is provided adjacent its upper end with an inwardly projecting key or pin 21 which engages a corresponding longitudinal keyway 22 in said inner member, as 100 shown in Figs. 3 and 4. This keyway extends from the extreme upper end of the inner member to a point above the lower end thereof, so as to form a stop-shoulder 23 and thereby prevent the complete withdrawal of the inner member from the outer member during the adjusting operation. In assembling the two members 14, 15, the inner member is inserted through the lower end of the outer member, and to facilitate 110 the registering of the keyway 22 with its key, a gage mark 24 is provided at the lower

end of the outer member which is in alinement with said key.

One side of the movable telescopic member is flattened as shown at 25 in Figs. 2 and 4, 5 and is provided thereon with a pitch scale 26, the graduations of which are adapted to be brought into alinement with the upper edge of the turning head 17 for the particular pitch desired. In the drawings, 10 the attachment is shown as adjusted to the pitch corresponding to "I" on the scale, as clearly shown in Fig. 2.

In Fig. 6 is shown a double-reed mouth-piece 27 connected to the improved attachment and illustrating another form of its application.

In the use of this pitch adjusting attachment, the same is substituted for the tube or conduit usually connected to the stem of 20 the instrument for obtaining the desired pitch, a different length of tube being usually employed for a predetermined pitch. When once applied to an instrument, this attachment is in position to be adjusted to any 25 pitch desired by simply rotating the turning head 17 in one direction or the other to effect a corresponding longitudinal movement of the inner telescopic member 14 relatively to the outer telescopic member 15 and there- 30 by shorten or lengthen the same to obtain the desired pitch.

While affording a simple means of adjusting the pitch of an instrument to suit various requirements, this attachment is a self-contained unit applicable to any wind instrument of the character described without

altering its construction. Furthermore, it eliminates the use of substitute parts which were heretofore employed for changing the pitch of such instruments.

I claim as my invention:

1. An attachment for adjusting the pitch of wind musical instruments comprising inner and outer tubular telescopic members, the outer member being adapted for engagement with the stem of the instrument and provided at its front end with an external annular flange and the inner member being movable relatively to said outer member and having an external screw thread, a nut engaging with the front side of said flange and having its thread engaging with the thread of said inner member, a tubular head engaging with the periphery of said nut and extending along the periphery of said external flange and provided with an internal flange at its rear end which engages with the rear side of said external flange.

2. An attachment for adjusting the pitch of wind musical instruments comprising inner and outer telescopic members, the outer member being adapted for engagement with the stem of the instrument and the inner member being adapted to receive the mouth-piece of the instrument, and means carried by said outer member for moving the inner member lengthwise relatively thereto, said inner member being provided with a longitudinally flattened area which is provided with a longitudinal pitch scale.

RAFFAELE PINNAVAJA.
